UNITED STATES PATENT OFFICE

2,025,090

EXCAVATING DIPPER

Paul Burke, Green Bay, Wis., assignor to Northwest Engineering Corporation, Green Bay, Wis., a corporation of Wisconsin

Application October 7, 1933, Serial No. 692,603

17 Claims. (Cl. 214—145)

The invention relates to dippers for excavating or dredging machines and has more particular reference to a novel construction which simplifies the conventional parts of the dipper resulting in a substantial weight reduction with corresponding increase in cubic capacity.

An object of the invention is to provide a dipper in which the back thereof is integrally joined with the dipper handle and which has adjustable connection with the body portion of the dipper to vary the inclination which the excavating teeth make with the handle. In the present construction clamping or bolting of the dipper handle to the back is therefore eliminated with the elimination also of all local duplication of weight so that the volume capacity can be correspondingly increased.

A further object is to provide a dipper in which the back thereof connects with the dipper handle by means of a plurality of plates secured as by welding to each other, and in which the back is secured to the sides of the dipper body by means of detachable securing pins so that the angle which the excavating teeth make with the handle may be altered to suit different conditions.

Another object is to provide a dipper in which the back is adjustable with respect to the sides of the dipper and wherein the sides are each provided with an extension for hingedly mounting a door on the body.

A further object is to provide a dipper in which the body has a plurality of angular adjustments with respect to the back with the latter having a dipper door hingedly mounted thereon for association with the body.

A further object is to provide a dipper of sturdy and rugged construction and which will fulfill all requirements of service and manufacture.

With these and other objects in view, the invention may consist of certain novel features of construction and operation, as will be more fully described and particularly pointed out in the specification, drawings and claims appended hereto.

In the drawings which illustrate an embodiment of the device and wherein like reference characters are used to designate like parts—

Figure 1 is a vertical sectional view taken to one side of the center of the dipper showing the same constructed in accordance with the present invention;

Figure 2 is a front elevation view of the dipper shown in Figure 1;

Figure 3 is a rear elevational view of the dipper

with a section of the door broken away to show the pivotal connection of the back with the dipper sides;

Figure 4 is a view similar to Figure 1 but showing the dipper in a different position of inclination with respect to the handle;

Figure 5 is a horizontal sectional view taken substantially on line 5—5 of Figure 3 and showing the dipper back in plan;

Figure 6 is a detail sectional view taken substantially along line 6—6 of Figure 1;

Figure 7 is a detail sectional view taken substantially along line 7—7 of Figure 4; and

Figure 8 is a vertical sectional view taken on a plane passing through the securing means for adjustably uniting the dipper back with the body and showing structure for hingedly mounting the door to the back.

Referring to the drawings the dipper comprises an integral body portion providing sides 10 and 11 which merge into a dipper front 12 carrying at its forward end a plurality of excavating teeth formed by the shanks 13 each having a detachable dipper tooth 14. The body portion is of any suitable material such as manganese steel of the required thickness and which tapers at 15 along the forward edge to a reduced thickness as shown in Figure 2. On the upper edge of the sides of the body portion are formed bosses 16, Figure 6, and extensions 17, Figure 7, the former providing means for securing the dipper side to the handle as will be more particularly described, while the extensions 17 are bifurcated for receiving the supporting ribs of the dipper door, thus pivotally securing the door to the body portion.

The dipper door is formed of a one piece casting shaped to provide a concavity on the side positioned adjacent the body portion and having an arcuate portion of determined curvature at its upper end to provide a flange 20 disposed substantially parallel with the dipper front. On the outside of the door are provided reinforcing ribs 21 and the supporting ribs 22, a supporting rib being located adjacent each side edge of the door and projecting beyond the flange 20 for pivotal connection by means of the pins 23 to the bifurcated extensions 17. The central reinforcing rib 21 slidably receives the latch 24 which projects beyond the door for connection with the keeper 25 formed integral with the dipper front 12. The latch 24 is operated to withdraw the end thereof from the keeper by means of a lever 26 pivotally connecting therewith and which lever is pivotally supported at 27 by the adjustable bracket 28. The outer end of the lever is adapted

to engage the boss 29 for limiting the rotation thereof when the keeper is being withdrawn.

The invention provides an adjustable connection between the dipper back formed by the plate 30 and the body portion of the dipper in order that the excavating teeth 14 may have different positions of inclination with respect to the dipper handle. An additional feature of the invention is the rigid connection of the dipper handle with the back which structure will now be described.

The handle is formed of a pair of sticks, preferably of hollow construction, each having a front wall 31, a rear wall 32 and inner and outer side walls 33 and 34, respectively. A plate 52 is secured by welding to each stick respectively and to the dipper back 30, providing supporting surfaces for the bail lugs 35 likewise welded to the upper surface of the back 30 and to the plate 52, which plate in effect forms a continuation of the inner wall of the dipper stick. The dipper sticks are spaced and thus space the lugs 35 which receive the bail 36 pivotally connecting therewith by means of pin 37. The dead end of a cable 38 is tied to the bail by which the dipper is lifted in the act of digging. The front wall 31 of each stick terminates short of the plate and has welded thereto a front plate 40 of substantially trapezoidal shape, the weld between the wall of the plate being reinforced by welding thereto the metal strip 41.

As the plate is welded at its base to the surface of the dipper back 30 the same in effect provides a continuation of wall 31, materially increasing the strength of the joint by the additional width of the base of the plate. The outer wall 34 of each dipper stick likewise has welded to its terminal end a side plate 42 of trapezoidal shape, the weld between the plate and wall being reinforced by the strip 43. This plate may form a continuation of its companion plate 40 or may comprise a separate plate, in which case their common edge is welded to make for a secure union. As more clearly shown in Figures 5, 6 and 7 the lower edge of each side plate 42 depends below the plate 30 and is located within the side members 10 and 11 of the body portion. Welded to the inside of each plate 42 at the respective sides thereof are reinforcing plates 53 and 54, each reinforcing plate and also plate 42 being suitably welded to form a secure union with plate 30 forming the back of the dipper. Plates 53 and 54 strengthen their respective plate 42 and have a contour at their base similar to that of the plate, extending upwardly a distance 55 above the dipper back as shown in Figures 6 and 7.

Each reinforcing plate 53 is apertured as is also plate 42, which opening is aligned with opening in boss 16 for receiving the securing bolt 46 pivotally uniting in this manner the respective dipper sides to the dipper back. Each plate 54 is likewise apertured, the opening extending through plate 42 for association with the several pairs of openings 47 and 48 formed in the boss 17 on the sides of the body. The securing bolts are located in the aligned apertures to secure the dipper body and back in the several positions of adjustment. It will be noted that with the lower pair of apertures 47 aligned with those provided by plate 42 and the reinforcing plate 54 the dipper has the inclination of Figure 1, while in Figure 4 the rear of the body portion has been in effect lowered to align the upper pair of apertures 48. With the parts united by securing bolts 49 in this position the angle of inclination which

the excavating teeth make with the dipper handle is greater than that of Figure 1, so that the structure permits adjustment of the body portion in order to vary this inclination to suit different conditions.

Completing the connection between each dipper stick and the back is a rear plate 55 extending from wall 32 and being welded thereto and along its sides to its respective plates 42 and 52. It may be here noted that each plate 52 is suitably welded along its other edge to a front plate 40 so that it may be said that each stick is securely united to the dipper back in fixed relation thereto. The sticks are joined at a point well above the dipper back by the transverse plates 56 welded to each other and having their abutting ends welded to the inside wall 33 of the sticks.

The detachable securing means provides for uniting the dipper body with the back, with the body in various positions of adjustment with respect thereto, and since the back and dipper sticks are in effect one the body therefore has various positions of inclination with the sticks. As the door 18 is hinged secured to extension 17 on the respective side members of the body the dipper back is located in various positions with respect thereto and in order that the same may at all times have association with the upper edge of the door the invention provides a built-up flange 57 welded to the left hand edge of the plate 30 and confined between the plates 52. The flange extends the full width of the back and as shown in Figure 1 has association with the upper edge of the door 18 which edge is provided with an upstanding boss 58. When the dipper body and back are in the position shown in Figure 4 the upper edge of the door, by means of the boss 58, is associated with the dipper back so that in both positions of adjustment of the dipper body the door in closed position provides an effective closure therefor.

The invention is not restricted to the pivotal mounting of the dipper door to the sides of the body but is to be considered as covering a modified construction in which the dipper door has 45 pivotal securing to the dipper back as shown in Figure 8. The portion of plate 42 in the vicinity of the reinforcing plate 54 is further reinforced by a triangular metal block 60 suitably secured as by welding to the exterior of the plate 42. 50 The respective rib 22 of the door is pivotally mounted to the block, plate 42 and the inside plate 52 by a pivot pin 62 of tapering formation which is held in place by a securing nut 63 having threaded connection with the end projecting 55 beyond the inside plate. It will be noted that for the purpose of providing a vertical bearing surface for the securing nut the base portion of plate 52 is bent to extend vertically in the vicinity of the reinforcing plate 54. A metal strip 64 60 is added to the exterior thereof above the flange 57 for strengthening purposes, the same being united to plate 52 by welding. As the triangular block 60 provides a vertical exterior surface, and which has projecting at right angles thereto the 65 pivot pin 62, it will be seen that the ribs 22 of the door, suitably extended for the purpose, may be mounted on the pivot pin and thus suspended for free pivotal movement from the dipper back. Angular adjustment of the dipper body with respect thereto is possible as heretofore described although a change in the position of the dipper body will necessitate a change also in the hinging of the door on the dipper back. Accordingly, a second opening 61 is provided in metal block 60 75

- in spaced relation to pivot pin 62 and which is tapered to receive said pin to lower the hinge connection of the door a distance equal to the change in the position of the dipper body.
5. An excavating dipper constructed in accordance with the invention is considerably reduced in weight due to the rigid connection of the dipper handle with the dipper back. The arrangement of plates welded to each other, to the dipper sticks and back eliminates considerable weight, with the result that the volume capacity of the dippers is correspondingly increased. This result is secured without any sacrifice in strength or rigidity of the connecting parts while an added 10 advantage is secured in the detachable connection between the back and the dipper body whereby the latter may be secured in various positions of inclination with respect to the handle.
- It is to be understood that I do not wish to be limited by the exact embodiment of the device shown, which is merely by way of illustration and not limitation, as various and other forms of the device will of course be apparent to those skilled in the art without departing from the 15 spirit of the invention or the scope of the claims.
- I claim:
1. In a dipper for excavating, dredging and similar machines, a dipper body, a dipper handle having means rigid therewith providing the back of the dipper, and securing means for detachably uniting the back to the sides of the body, certain of said means having different positions of location in the sides of the body to vary the inclination of the body with the dipper handle.
  2. In a dipper for excavating, dredging and similar machines, a dipper body formed by a member of substantially U-shaped cross section, the base thereof providing the front of the dipper and the legs forming the side members of the dipper, a back for the body secured to the side members, and a bifurcated extension formed on the end of each of said side members for pivotally securing a door to the body.
  3. In a dipper for excavating, dredging and similar machines, a dipper body formed by a member of substantially U-shaped cross section, the base thereof providing the front of the dipper and the legs forming the side members of the dipper, a back for the body secured to the side members, a handle rigidly secured to the back, and means formed on the end of each of said members to one side thereof for pivotally securing a door to the body.
  4. In a dipper for excavating, dredging and similar machines, a dipper body formed by a member substantially U-shaped in cross section, the base thereof providing the front of the dipper and the legs forming the side members of the dipper, a back for the body formed by a plate detachably secured to the side members, a handle rigidly secured to the plate, and an extension on each side member for hingedly mounting a door to the body.
  5. In a dipper for excavating, dredging and similar machines, a dipper body formed by a member substantially U-shaped in cross section, a plate forming the back of the dipper, a handle for the dipper, means welded to the handle and plate for uniting the parts, said means depending from the plate and being secured to the sides of the member.
  6. In a dipper for excavating, dredging and similar machines, a dipper body providing side members, a plate forming the back of the dipper, dipper sticks providing the handle of the dipper, and a plurality of plates welded to the sticks and back to fixedly unite the sticks thereto, certain of said plates depending below the dipper back and being secured to the side members.
  7. In a dipper for excavating, dredging and similar machines, a dipper body providing side members and having a door hingedly secured thereto, a plate forming the back of the dipper, dipper sticks providing the handle of the dipper, and a plurality of plates welded to the sticks and back to fixedly unite the sticks thereto, certain of said plates depending below the dipper back and being secured to the side members.
  8. In a dipper for excavating, dredging and similar machines, a dipper body providing side members, said members having bifurcated extensions for hingedly mounting a door, a plate forming the back of the dipper, a pair of dipper sticks providing the handle of the dipper, and a plurality of plates welded to the back and to each stick to fixedly unite the back to the sticks, certain of said plates depending below the dipper back and being detachably secured to the side members.
  9. In a dipper for excavating, dredging and similar machines, a dipper body having a door pivotally secured thereto, a dipper handle having a plate rigid therewith providing the back of the dipper, securing means for detachably uniting the back to the sides of the body in various positions of adjustment, and a flange on the dipper back for association with the door in said various positions of adjustment of the back with the dipper body.
  10. In a dipper for excavating, dredging and similar machines, a dipper body having a door pivotally secured thereto, a dipper handle having a plate rigid therewith providing the back of the dipper, securing means for detachably uniting the back to the sides of the body in various positions of adjustment, and a built-up flange welded to the dipper back, said flange having association with the upper edge of the door in said various positions of adjustment of the back with the dipper body.
  11. In a dipper for excavating, dredging and similar machines, a dipper body having a door pivotally secured thereto, a dipper handle having means integral therewith providing the back of the dipper, and securing means for detachably uniting the back to the sides of the body, certain of said means having different positions of location in the sides of the body to vary the inclination of the body with the dipper handle.
  12. In a dipper for excavating, dredging and similar machines, a dipper body, a dipper handle having a plate rigid therewith providing the back of the dipper, securing means for detachably uniting the back to the sides of the body in various positions of adjustment, and means fixed to the back of the dipper for pivotally securing a dipper door thereto.
  13. In a dipper for excavating, dredging and similar machines, a dipper body, a dipper handle having means integral therewith providing the back of the dipper, securing means for detachably uniting the back to the sides of the body, certain of said securing means having different positions of location in the sides of the body to vary the inclination of the body with the dipper handle, and a pivot pin fixed to the dipper back for pivotally securing a dipper door thereto, said pin having different positions of location in the

- dipper back to vary the position of the door to accord with the adjustment of the dipper body.
14. In a dipper for excavating, dredging and similar machines, a dipper body having side members, a plate forming the back of the dipper, dipper sticks providing the handle of the dipper and having plate members welded thereto and to the back to fixedly unite the handle and back of the dipper, certain of said plates depending below the back for detachably securing the dipper body in various positions of adjustment with respect to the handle, and means fixed to the back for pivotally securing a dipper door thereto.
15. In a dipper for excavating, dredging and similar machines, a dipper body having side members, a plate forming the back of the dipper, dipper sticks providing the handle of the dipper and having plate members welded thereto and to the back to fixedly unite the handle and back of the dipper, certain of said plates depending below the back for detachably securing the dipper body in various positions of adjustment with respect to the handle, and a pivot stud detachably secured to the dipper back for pivotally securing a door thereto, said stud having different positions of location in the back to vary the position of the door to accord with the adjustment of the body.
16. In a dipper for excavating, dredging and similar machines, a dipper body of substantially U-shape in cross section, the base thereof providing the front of the dipper and the legs forming the side members of the dipper, a dipper handle having a plate fixed to the end thereof providing the back of the dipper, means securing the body to the back in a plurality of adjusted positions with respect to the handle, and a pivot stud carried by the back for pivotally securing a door thereto, the position of said stud being adjustable to accord with the various positions of adjustment of the body.
17. In a dipper for excavating, dredging and similar machines, a dipper body, a dipper handle having means rigid therewith providing the back of the dipper, and securing means for detachably uniting the back to the sides of the body, certain of said means having different positions of location with respect to the body to vary the inclination of the body with the dipper handle.

PAUL BURKE. 25
